To all whom it may concern:

Be it known that we, Walter F. Brotzman and Benjamin Harry Statter, citizens of the United States, residing at Baltimore, in the State of Maryland, have invented a new, original, and ornamental Design for a Phonograph Record Rack, of which the following is a specification, reference being made to the accompanying drawing, forming a part thereof, in which:

Fig. 1 is a front elevational view of the phonograph record rack, showing our design;
Fig. 2 is a side elevational view; and
Fig. 3 is a top plan view thereof.

We claim:

The ornamental design for a phonograph record rack, as shown.

WALTER F. BROTZMAN.
BENJAMIN HARRY STATTER.
